UNITED STATES PATENT OFFICE.

CHARLES S. BURTON, OF OAK PARK, ILLINOIS.

CONTAINER FOR MUSIC ROLLS AND THE LIKE.

1,402,917.

Specification of Letters Patent. Patented Jan. 10, 1922.

Application filed December 26, 1919. Serial No. 347,404.

To all whom it may concern:

Be it known that I, CHARLES S. BURTON, a citizen of the United States, and a resident of Oak Park, in the county of Cook 5 and State of Illinois, have invented certain new and useful Improvements in Containers for Music Rolls and the like, of which the following is a specification, reference being had to the accompanying drawings, 10 forming a part thereof.

The purpose of this invention is to provide an improved construction of a container for music rolls or the like, particularly designed for permitting the withdrawal 15 of the contents from the end of the container while such containers are stacked in piles with only the ends exposed for access. It consists in the elements and features of construction shown and described, 20 as indicated in the claims.

In the drawings:—

Figure 1 is a vertical longitudinal section of the container embodying this invention, the same being shown in closed position with 25 the music roll therein.

Figure 2 is a similar view showing the closure withdrawn to a position for inserting or removing the roll, the roll being shown in the position which it occupies upon 30 withdrawal of the closure for removal of the roll.

Figure 3 is a section similar to the preceding figures, showing the closure withdrawn to the position for tilting down but 35 not tilted down, showing its engagement with the roll for withdrawing the latter.

Figure 4 is a section at the line, 4—4, on Figure 2.

The structure shown in the drawings comprises an outer tubular casing, A, which 40 preferably has one end closed as shown at A¹, and the other end open for receiving an interiorly telescoping closure member, B, which is shown open topped comprising an 45 outer end, B¹, sides, B², B², and bottom which is preferably as shown in two parts, B³ and B⁴, hinged together at the line b³, corresponding to a limit of withdrawal of 50 the closure from the box in operation. It 55 will be observed that the sides, B², B², extend rearward beyond the withdrawal or hinge line of the bottom of the closure, said extensions b², b², being greater than the height of the tubular casing. These extended sides b², b², are cut away at their upper edges so that the closure may pivot 60 over the hinge line between the forward and rear sections of the bottom members, B³, B⁴, when the closure is withdrawn so that said hinge line has arrived at the forward 60 edge of the bottom of the casing, as seen in Figure 2. It will be understood that the extension of the side beyond the vertical plane of the hinge line of the bottom being greater than the height of the casing will prevent 65 the closure member from swinging down pivotally about the hinge line so far as to withdraw the extended side entirely out of the casing when the closure has not been withdrawn farther than so as to bring the 70 hinge line as stated at the forward edge of the casing bottom. Preferably and designedly the upper edges of the side extensions, b², b², are cut away only substantially as far as 75 shown in the drawings,—that is, so much as to permit the forward section to swing down to a position shown in full line in Figure 3, at which the forward end B¹, of said closure 80 is out of the path of withdrawal of the roll which, by means hereinafter explained, is withdrawn with the closure so that its end 85 protrudes directly from the tubular casing in the space occupied by the closure before the latter has been swung down,—that is, before it is swung from the position shown in full line to that shown in dotted line in Figure 3; and the roll can be slightly lifted to clear the down-swung end of the closure. This is preferable to permitting the closure 90 to swing down so far as to clear the roll without lifting it for reasons hereinafter explained. The simplest form in which the rear extensions, b², b², of the sides, B², B², of the closure may be cut away for the purpose indicated, is that shown in the drawings, 95 in which they are cut in the arc of a circle about the hinge pivot with a radius substantially the interior height of the tubular casing (which will be substantially the exterior height of the closure), said arc being the measure of the angle through which the closure will be required to swing down in order that its forward end may clear the path of withdrawal of the roll as indicated. The cut of the upper edge of the extensions, b², b², then continuing in a line 100 tangent to said arc at its rear end as shown in the drawings. It will be understood that the only essential requirement in respect to the matter of cutting away the upper edges 105 of these extensions, b², b², is that at the rear ends they shall be at such height as to per-

mit the downward swing of the forward section to any desired position for withdrawal of the roll. That is, they may be cut away more than this but not less, intermediate 5 their rear ends and the point at which said cutting away begins.

The importance and advantage of having the rearward side extensions, b^2 , of the telescoping closure provided and formed as described, so that they shall not be withdrawn 10 from the tubular casing in withdrawing the closure to a point at which it may be swung down to permit the withdrawal of the roll, so that thereby these side extensions remain 15 always engaged with the tubular casing, so that the closure may be always without difficulty or inconvenience swung up into position for telescoping into the casing. In 20 structures for similar purposes which have heretofore been suggested, the telescoping closure or "drop-end" of the casing has been proposed either having its sides terminating substantially at the transverse plane of the hinge joint of the bottom or with the bottom lacking the hinge joint. With the first 25 mentioned of these heretofore proposed constructions, difficulty or inconvenience is experienced in restoring the closure to telescoped position within the casing, because 30 when such boxes are accumulated in a pile, which is the desired manner of using them, the withdrawal of the closure deprives the tubular member of the reinforcement of the forward end of the closure, and the weight 35 of the super-incumbent boxes tends to sway the lower boxes thus deprived of reinforcement, sideward, distorting them into trapezoidal form; and then when the closure is 40 swung up and thrust rearward, the rear edges of its sides encounter the lateral edges.—displaced sideward,—of the casing, and prevent the re-entrance of the closure into the casing, compelling the user to employ some means of straightening up to 45 distorted tubular casing or to distort the telescoping closure in order to enter it within the distorted casing. When the distortion is slight and unnoticed; the result is that the two encountering ends of the sides of the 50 tubular casing and of the closure, respectively, soon mangle each other, increasing the difficulty and inconvenience of re-entering the closure into the tubular casing, besides producing a disheveled and untidy appearance. These difficulties are avoided by 55 the construction shown, involving the continued engagement of the extended sides b^2 , b^2 , of the closure in the tubular casing when the closure is withdrawn and swung down 60 for the withdrawal of the roll. With the second mentioned heretofore proposed construction, the down-tilting of the closure swings the bottom of the closure up obliquely across the cavity of the tubular member; and this 65 is impossible when the box content is a music

roll or the like which cannot be displaced by such intrusion of the said bottom of the closure.

It is desirable to provide means for definitely stopping the withdrawal of the closure at the point at which it is to be swung down,—that is, so that the hinge line of the bottom of the closure is at the forward edge of the bottom side of the case. For this purpose there is provided a catch, D, to be carried by the rear member, B^4 , of the bottom of the closure, which is adapted to have its nose D^1 , engage an aperture a^1 , made in the bottom side of the casing near the forward end. This catch is seen engaging the forward side of the aperture when the closure is withdrawn so that the hinge line coincides substantially with the forward edge of the bottom of the casing, checks it for swinging it down about the hinge line as desired. The rear shoulder of the catch nose is made sloping so that it rides out of the aperture readily upon the inthrust of the closure.

An objection of the employment of tubular containers of this general character having telescoping closures for the purpose of music rolls, consists in the liability of the interior member or closure and the roll therein, to slide out of the casing while the boxes are being carried from place to place 90 in the process of packing and shipment or merchandising, with the result that the roll ends are liable to be broken by the fall. This can be prevented only by some locking device for retaining the closure within the 95 tubular casing or making the closure fit so tightly in the casing that the frictional resistance will prevent it from sliding out. The frictional resistance method is objectionable, because if the friction is sufficient 100 to prevent the closure from sliding out of the casing under the circumstances indicated, it is liable to be so great as to make it difficult to withdraw the closure from the casing when the boxes are stacked or piled in their 105 position of use, without pulling the entire container out of the pile, because the superincumbent load upon the lower boxes of the pile, in view of the unavoidably yielding character of the boxes,—made of pasteboard,—greatly increases the friction. A catch which has to be manipulated independently of the operation for withdrawing the closure is objectionable, because the user 110 will frequently forget and omit to release the catch before he pulls upon the closure to withdraw it; and damage to the box, consisting either of pulling off the withdrawing lug or mutilating the catch engagement is certain to be incurred. To meet this difficulty there is provided in the present construction a catch which is released by the action of the closure-withdrawing lug so that the operator pays no attention to the catch, but only withdraws the closure as if 115 120 125 130

there were no catch. The device for this purpose consists of a catch, E, similar to the catch, D, carried by the forward member of the bottom of the closure, having its catch 5 nose, E¹, extending out through an aperture, b⁴, in said bottom for engaging the same aperture, a¹, in the lower side of the casing which is provided for engagement of the catch nose, D. The lug, F, provided for 10 withdrawing the closure from the casing has its inner end secured to the bottom, B³, of the closure, its length extended out under the catch, E, up around the catch nose, and thence out to the forward side of the forward end of the closure for manual manipulation. It will be seen that when the user 15 seizes the protruding lug to withdraw the closure, the first effect of his pull upon it is to disengage the catch nose, E¹, from the aperture, a¹, of the casing, continued pull withdrawing the closure from the casing. The head of the catch is formed so that when the pull upon the lug disengages it from the aperture, a¹, of the casing, its shoulder, e², 20 is lifted up under the roll behind the head thereof, and engages the roll by means of said head, so that the roll is withdrawn with the closure, and is thereby in position to be taken hold of easily for removing it from 25 the casing.

I claim:-

1. A container for the purpose indicated comprising an outer tubular casing and an inner telescoping closure; means for checking 35 the withdrawal of the closure at a predetermined point and for pivoting it at withdrawn position at the forward edge of the bottom side of the casing; a catch carried by the bottom side of the closure, the 40 bottom side of the casing having co-operating means for engaging said catch at closed position of the closure, and flexible means connected to the closure for withdrawing it from the casing, engaging the catch for 45 withdrawing it from the co-operating means on the casing bottom in the movement for withdrawing the closure from the casing.

2. In the construction defined in claim 1

foregoing, the closure-withdrawing means being a strip having its inner end secured 50 to the bottom of the closure and extending from its securement along under the catch nose, thence up in front of the same and out through the end of the closure for manual engagement.

3. A container for the purpose indicated, comprising an outer tubular casing having an open end and a closed end and an interior telescoping closure for the open end of the casing, a spring catch carried by the bottom 60 side of the closure, said bottom side having an aperture through which the nose of the catch protrudes, the casing having an aperture in its lower side for engagement of the catch nose, said catch being adapted upon 65 being lifted out of engagement with the aperture of the casing to protrude upwardly within the casing for engaging behind the head of the music roll, and means for withdrawing the closure from the casing secured 70 at its inner end to the bottom of the closure and extending under the catch and up in front of the same and then out through the forward end of the closure for manual engagement; whereby upon pulling said 75 withdrawing means the catch nose is lifted out of engagement with the casing and into engagement with the head of the roll, and subsequent pull withdraws the roll with the closure.

4. A container for the purpose indicated comprising an outer tubular casing and an inner telescoping closure, the bottom side of the closure comprising a forward part and a rear part hinged together at a transverse 85 line which is the limit of withdrawal of the closure, the lower side of the casing having an aperture near the forward end and a catch for engagement of said aperture carried by the rear hinged member of the closure bottom.

In testimony whereof, I have hereunto set my hand at Chicago, Illinois, this 22nd day of December, 1919.

CHARLES S. BURTON.
